Primary Examiner — Jennifer O King

(57) **CLAIM**

I claim the ornamental design for a stationary wall mount for storing a portable electric vehicle charger, as shown and described.

DESCRIPTION

FIG. 1 is a top perspective view showing a stationary wall mount for storing a portable electric vehicle charger of my new design;

FIG. 2 is a front plan view thereof;

FIG. 3 is a top plan view thereof;

FIG. 4 is a side plan view thereof;

FIG. 5 is a bottom plan view thereof;

FIG. 6 is a side plan view thereof opposite FIG. 4; and,

FIG. 7 is a rear plan view thereof.

The broken lines shown represent environment and form no part of the claimed design.
